UNITED STATES PATENT OFFICE.

FREDERICK A. LINGSCH, OF NEW YORK, N. Y.

PIANO-ACTION.

1,296,826.

Specification of Letters Patent. Patented Mar. 11, 1919.

Application filed July 7, 1917. Serial No. 179,250.

To all whom it may concern:

Be it known that I, FREDERICK A. LINGSCH, a citizen of the United States, residing in the city of New York, borough of Bronx, 5 county of Bronx, and State of New York, have invented a certain new and useful Piano-Action, of which the following is a specification.

This invention is a piano action and, more 10 particularly, an action for upright pianos, being capable of use either through the manual actuation of keys or through the automatic operation of player mechanism.

The object of the invention is to greatly 15 simplify and strengthen some of the operating parts of the action for the purpose of rendering them more durable and lasting, and more easily regulable.

A further object of the invention is to construct 20 each hammer so that, when a plurality of them are positioned side by side within a case, and the front of said case removed, said hammers will present a uniform and neat appearance.

25 Features of the invention, other than those specified, will be apparent from the herein- after detailed description taken in conjunction with the accompanying drawings.

In the accompanying drawings I have 30 illustrated one practical embodiment of the invention, but the construction therein shown is to be understood as illustrative, only, and not as defining the limits of the invention.

Figure 1 is a side elevation of a unit of a 35 piano action embodying the present invention, the parts being shown in normal, inactive position.

Fig. 2 is a view similar to that of Fig. 1, but with the parts shown in the positions of 40 which they assume immediately after the key is operated, and before the string is struck.

Fig. 3 is a fragmental elevation showing, on an enlarged scale, that portion of the 45 unit embodying the hammer butt, the upper end of the jack or fly, and the appurte- nances of said parts, and

Fig. 4 is a fragmental elevation showing the positions of the parts in check.

50 Referring to the drawings, A indicates a string of a piano, which piano is provided with the usual main action rail B, hammer rest rail C, and bottom or tongue rail D. The hammer butt E of the action carries 55 the usual hammer E' on a stem e' and is supported by a flange e on the action rail, as shown. F is the jack, connected through

a flange f with the wippen G, mounted by means of the usual flange g upon the main action rail and actuated through an abstract H, the tongue h of which is pivotally connected to bottom rail D. I is the inner end of a key having an adjustable connection i with the lower end of abstract H.

J is the damper, which is operated from 60 wippen G through damper lever j and intermediate spoon j', the damper being normally held in engagement with the string A by a leaf-spring j², as is common. Hammer E' is normally maintained in retracted position, with its stem against hammer rail C, by means of a spring c mounted on a spring rail c'.

The jack is normally maintained in a retracted position by means of a spring f' positioned between a toe f² on Jack F and wippen G. Moreover, the upper face of the toe f² co-operates with a stop m adapted for adjustment by an adjusting screw m' threaded through a regulating rail M spaced from 75 the action rail B by the usual spacing members m², while threaded through the rigid stem l of the back check L is a similar adjusting screw l', carrying at its lower end a stop l², by which the rebound of the ham- 80 mer, after being struck, is limited.

In accordance with this invention, the adjusting means for the checking of the hammer is mounted upon, and is movable with, the jack, and, in the preferred form of the 90 invention, this means is embodied in a rocker K pivoted near the upper end of the jack, as at k. The rocker is provided with a depending portion or stem k', through which extends a screw k² which threads into the 95 jack and allows of pivotal regulation of rocker K. Said rocker is adapted to co-operate with a back check L which, in accordance with this invention, is rigidly mounted with respect to the hammer butt E by means 100 of a stem l, and is provided with suitable cushioning means l' in the form of leather, felt, or both. The front face of rocker K is similarly cushioned, but is shaped eccentrically of the point of pivoting of said 105 rocker, so that the manipulation of the adjusting screw k² will vary the distance between the nearest point of the front face of said rocker and the nearest point of the cushioned face of the back check L.

The operation of the device as described will be clear to those skilled in the art. If the parts are in the normal position shown in Fig. 1, and the key I is actuated, the

wippen G is oscillated upwardly and shifts the jack F, which, being in engagement with the forward, inclined face of the hammer butt, causes the butt to rapidly rotate about 5 its flange e and throw the hammer E' sharply against the string A. Simultaneously with this operation, the rear end of the wippen, operating through spoon j', oscillates the damper lever j, thereby moving damper J 10 free from the string, the damper being in this position when the hammer engages the string. About the time, or just before, hammer E' strikes the string, as shown in Fig. 2, the toe f² of the jack engages with 15 the stop m, thereby causing the upward movement of the jack to cease and changing said upward movement into a sharp forward movement of the upper end of the jack to bring the cushioned face of rocker K 20 into engagement with the cushioned face l' of back check L, all as clearly shown in Fig. 2. As the hammer rebounds from the string, the key I being held down momentarily, the jack retains substantially the same position 25 which it occupied in Fig. 2, but the inertia of the hammer causes the upper end of the jack and rocker to be wedged between the cushioned faces of the hammer butt and the back check, as shown in Fig. 4 in full lines. 30 the upper end of the jack and the cushioned face of the rocker pressing into the cushions on the hammer butt and the back check, respectively, as clearly shown.

The foregoing is the normal operation of 35 the action, but, if the key is struck an exceptionally heavy blow, the rebound of the hammer will, of course, be much greater than normally, and it is in order to preclude the wedging of the jack and rocker with such tightness between the hammer 40 butt and the back check as to unduly strain or break these parts, that the stop l² and adjusting screw l² are provided. When such heavy blow is struck, the rebound of the 45 hammer may cause said hammer and its associated parts to assume the dotted line position of Fig. 4, in which event the cushioning stop l³ will engage with the upper portion of the rocker, as shown in the dotted line 50 position, thereby precluding the jack and rocker from becoming too tightly wedged between the hammer butt and the back check and preventing breakage or undue straining of the parts. It will, of course, be understood that, when the key is released, it assumes its normal position, allowing the jack 55 to drop back to the position shown in Fig. 1, and the hammer stem e' to engage with the hammer rail C. By employing the construction described, the parts are subjected 60 to the least possible strain, and the wedging action of the jack and rocker between the hammer butt and back check cushions the

parts against a too sudden stop, while the cushioning stop l³ precludes this wedging 65 action from proceeding to too great an extent.

A piano made in accordance with the present invention possesses many features of advantage. For example, the positioning of 70 the regulating means, in the form of rocker K, on the jack assures, at all times, a true alinement of the back checks of the successive actions, so that, when the front of the piano case is opened, all of these checks are in perfect alinement, and a much neater and more esthetic appearance results than is possible where the regulating means is mounted upon the back check or the back check made bodily adjustable. Moreover, a much stronger construction results from the mounting of the back check rigidly upon the hammer butt E through the intermediate stem l. This is an important consideration, since the question 75 of cross-grains in the wood from which the action is formed does not arise in the rigid construction referred to. By mounting the regulating means directly upon the jack, the alinement is preserved and a much stronger and more rigid and durable construction results without, in the least, sacrificing any degree of regulation.

Another advantage possessed by the present invention is that, by making the back check rigid and mounting the regulating 95 means on the jack, the depth of the action is minimized so as to allow of more space in the case for player mechanism, if the action is to be used in combination therewith. I have shown the action as operated 100 from a key I, but its application to player pianos will be manifest to those skilled in the art.

While I have shown and described one embodiment of my invention, it is to be 105 understood that it is not limited thereto, but is broad enough to cover all structures that come within the scope of the annexed claim.

Having thus fully described the invention, what I claim as new, and desire to secure by 110 Letters Patent, is:

A piano-action embodying a hammer butt, a back check rigidly mounted on the hammer butt and placed forward thereof, a jack provided at its upper end with a head to 115 coöperate with the front face of the hammer butt, a block pivoted to the jack at its upper end and provided with an eccentric face to engage the back check, and means mounted on the back check for limiting the return movement of the hammer butt after the hammer is operated.

In testimony whereof I have signed my name to this specification.

FREDERICK A. LINGSCH.
